UNITED STATES PATENT OFFICE.

WILLIAM S. BECHTOLD, OF NEWARK, NEW JERSEY.

DESIGN FOR THE BACK OF A MIRROR, BRUSH, OR SIMILAR TOILET ARTICLE.

58,421.

Specification for Design.

Patented July 19, 1921.

Application filed January 13, 1920. Serial No. 351,263. Term of patent 14 years.

To all whom it may concern:

Be it known that I, WILLIAM S. BECHTOLD, a citizen of the United States, residing at Newark, in the county of Essex and State of New Jersey, have invented a new, original, and ornamental Design for the Back of a Mirror, Brush, or Similar Toilet Article, of which the following is a specification, reference being had to the accompanying drawing, forming part thereof.

I claim:

The ornamental design for the back of a mirror, brush, or similar toilet article, as shown.

WILLIAM S. BECHTOLD.
